CLAIM

We claim the ornamental design for a bottle opener, as shown and described.

DESCRIPTION

FIG. 1 is a perspective view of our design of the bottle opener.

FIG. 2 is a top plan view of our design.

FIG. 3 is a bottom plan view of our design.

FIG. 4 is a left side elevation view of our design.

FIG. 5 is a right side elevation view of our design.

FIG. 6 is a front elevation view of our design; and,

FIG. 7 is a back elevation view of our design.
